UNITED STATES PATENT OFFICE.

MAURY W. HIBBARD, OF CHICAGO, ILLINOIS, ASSIGNOR TO RICHARD FITZGERALD, OF CHICAGO, ILLINOIS.

FLUID-PRESSURE BRAKE.

SPECIFICATION forming part of Letters Patent No. 699,386, dated May 6, 1902.

Application filed December 17, 1901. Serial No. 86,204. (No model.)

To all whom it may concern:

Be it known that I, MAURY W. HIBBARD, residing at Chicago, in the county of Cook and State of Illinois, have invented certain new and useful Improvements in Fluid-Pressure Brakes, of which the following is a specification.

My invention relates to fluid-pressure brakes generally; and one of its objects is to provide simple, efficient, and reliable valve mechanism capable of producing a partial braking pressure for a car empty and producing a full braking pressure for a car loaded, the valve mechanism in its present and herein-illustrated form also providing means for regulating the brake-cylinder pressure as well as providing for the release or "bleed" of the auxiliary reservoir. Furthermore, in its preferred form herein described my valve mechanism is arranged to be operated by the ordinary and well-known bleed-rods or equivalents thereof in such manner that the usual pull thereon will bleed or release the auxiliary reservoir as heretofore, while the new movement or inward push of those rods will set or adjust the valve mechanism to "loaded-car" position from a normal adjustment of "empty-car" position. Another and important object of my invention is to provide means, herein styled a "controller," coöperating with the valve mechanism above described for the purpose of automatically holding such mechanism to loaded-car position when so adjusted and to hold it there so long as the car remains charged with fluid-pressure and then to automatically restore the valve mechanism to its normal adjustment of empty-car position, this restoration occurring in the apparatus shown herein whether the car has been unloaded or remains loaded.

In the drawings, Figure 1 is a plan view of the well-known parts of the air-brake equipment of a car, showing a form of relative arrangement of my apparatus; Fig. 2, an elevation of the valve device with a portion thereof broken away or in section to show the valve-chamber and valve; Fig. 3, an elevation of the valve mechanism proper and a section of the controller and illustrating empty-car position; Fig. 4, a section of the

valve mechanism, illustrating loaded-car position; Fig. 5, a similar section, but illustrating bleed position; Fig. 6, a section of the valve mechanism and corresponding to Fig. 3 in the position of the valve; Fig. 7, a section of my pressure-regulating device or blow-down; Fig. 8, a plan of the valve-seat; Fig. 9, a plan of the valve; Fig. 10, a plan of the valve, showing below the valve-seat ports and relative positions of the valve and seat in loaded-car position; and Fig. 11, a view similar to Fig. 10, but illustrating bleed position.

My device works in connection with and as a part of the usual air-brake system, as clearly illustrated in Fig. 1, comprising the ordinary train-pipe 1, triple valve 2, auxiliary reservoir 3, and brake-cylinder 4, to which is added the supplemental reservoir 5, which latter answers in arrangement and functions to the similar supplemental reservoir shown in my prior patent, No. 683,205, issued September 24, 1901.

In Fig. 1 is shown for the sake of a full comprehension of my invention the general arrangement and relation of the various elements of the air-brake system just mentioned, the car-sills being indicated by dotted lines. In this figure the valve device, which is here indicated as a whole by the reference character 6, has connection with the auxiliary reservoir through the pipe 7, with the brake-cylinder through the pipe 8, and with the supplemental reservoir through the pipe 9. To avoid the necessity of providing special or additional holes in the auxiliary reservoir and brake-cylinder for these pipe connections, the auxiliary-reservoir pipe 7 may enter such reservoir through the bleed-opening therein, and the brake-cylinder pipe 8 may enter such brake-cylinder through one of the usual oil-holes, the plug of which has been removed.

The valve device consists in the present instance of a casing 10, having an interior chamber 11, which is normally closed by a screw-cap 12. (See Fig. 2.) This chamber contains a valve 13, here shown as of the rotary disk type and adapted to be operated by the detachable valve-stem 14, passing centrally through the screw-cap 12 and having within the valve-chamber a circular flange 15,

pressed against a suitable gasket 16 to form an air-tight fit or joint. As indicated in Figs. 4 and 5, the inner end of the valve-stem is rectangular to fit between and engage lugs 17, providing similar formation between them to thereby receive such valve-stem. The valve is kept to its seat 18 by a spring 19, which assists the air-pressure in this regard, and at the same time the valve-stem is held thereby in proper relative position.

As illustrated in Fig. 9, the valve 13 has two transverse ports 20 and 21 and a recess 22. The valve also has by preference a short bearing 23, received by a central socket 24 in the valve-seat. The valve works upon the valve-seat and is adapted to govern various ports and passages now to be described. Referring to Fig. 8, the valve-seat has a port marked 9, because it represents the termination of the passage from the supplemental reservoir through pipe 9, this port also being indicated by the letters "S. R." to denote "supplemental reservoir." Likewise the brake-cylinder connection or passage from pipe 8 enters the valve-chamber through the port marked 8 and is indicated by "B. C." to denote "brake-cylinder." A third port and passage 25 leads to a blow-down or pressure-regulating device and is therefore indicated by "B. D." A fourth port and passage 26, marked "Contr.," communicates with an automatic valve locking and restoring or controlling device, which forms one of the main features of my present invention. A fifth port 27 leads to the atmosphere and is marked "R. P." to denote "release-port."

The valve-chamber 11 communicates with the auxiliary reservoir through port and passage marked "7" the same as the pipe connection and is also marked "A. R." Opposite said port and passage there is a similar port 7^a, normally closed by a screw-plug 28. This port 7^a is desirable in case the rigging of any particular car will not permit of the arrangement of equipment, as shown in Fig. 1, in which event the port and passage 7 can be closed by the plug and connection be made with the auxiliary reservoir through said port 7^a. Furthermore, by removing the plug 28 the valve 50 can be oiled and a supply of oil introduced to fill the valve-chamber 11 up as high as the port 9. As oil is trapped within this chamber, a single oiling is sufficient to oil the valve for years. The auxiliary-reservoir port is 55 always open, and consequently the valve-chamber into which it directly enters is always filled with the same pressure as such reservoir.

The lever portion of the valve-casing has 60 an extension 29, in which screws the casing 30 of the blow-down device, which is a pressure-regulating valve adapted in service action to keep and in emergency to reduce the brake-cylinder pressure to a predetermined 65 minimum to which such valve device is adjusted, with the result in case of emergency action that the brake-cylinder is reduced as

the speed of the car decreases and the sliding of the wheels is prevented. As shown herein, (see Fig. 7,) this blow-down device or 70 pressure-regulator comprises a piston-head 31, movable in said casing 30 and having a valve-seat 32 normally pressed against the lower end of the tube 33 to close the passage there-through. A coiled spring 34, having the adjustable follower head or plate 35, presses against the piston, as described. The piston carries a stem 36, entering the tube or closed bushing 33 and having its upper end of increasing diameter (see Fig. 7) to govern the 80 exhaust-ports 37 in such manner that after an emergency application the excess of brake-cylinder pressure will have a slow initial release and a subsequently gradually-increasing release. This valve device is therefore a 85 pressure-regulator for a high-speed brake system or for the usual system. The blow-down port and passage 25 communicates with the chamber above the piston 31, as shown in full lines in Fig. 2 and dotted lines in Figs. 5 and 6. 90

The valve-stem is provided with an operating double lever pinned thereto, so as to have a single relative position thereon and having the two arms 38 and 39. The lever-arm 38 is pivotally connected to the usual bleed or release valve-rod 40, extending to one side of the car, while the lever-arm 39 is similarly connected to the other usual bleed-rod 41, so that the valve device may be operated from either side of the car by the train-men.

The valve-casing, as shown, has a tubular extension 42, into which screws a hollow casing 43. Extending centrally of the chamber 45^a thus formed is a valve-stem 44, having intermediate of its length a piston-head 45, adapted to slide in a bushing 46 and at loaded-car position to seat as a valve on a gasket forming a seat 47 at the inner end of said chamber. The valve-stem projects 110 from the extension 42 and is pivotally connected to the lever-arm 38 by means of a link 48, pivoted at one end between the two lugs 49 on the lateral branch 50 of the lever-arm 38 and at the other end to such valve-stem. (See Figs. 1, 2, and 4.) The side of the valve-casing 10 has a rib 51, (see Figs. 2 and 3,) through which extends the passage 26 from the valve-chamber 11 into the annular cavity 52 around the bushing 46. One 115 or more ports 53 extend through this bushing to connect said cavity with the valve-chamber within, all as clearly illustrated in Figs. 3, 4, 5.

The valve-stem 44 is held to normal position, as shown, Fig. 3, by the double-acting spring 54, which presses at one end against a follower-plate 55 and at its other end against another follower-plate 56, the latter preferably slidable in a bushing 57 and both loosely 130 mounted on the valve-stem. On the right-hand end of the stem 44, Fig. 3, a collar or ring 58 is pinned or secured in any suitable manner. As indicated in Fig. 3, which rep-

resents normal or empty-car position, the plate 55 is held projected by the spring until such plate abuts against the end of the bushing 46, and the plate 56 is likewise projected against the shoulder 59 in the casing 43.

The operation of the mechanism will now be explained. Starting with the valve set or adjusted to empty-car position, which is normal, as shown in Figs. 3 and 6, the braking is done with the usual auxiliary reservoir, inasmuch as the supplemental-reservoir port 9 is closed or lapped by the valve. In this position of the valve its recess 22 connects the brake-cylinder port 8 with the blow-down port 25, causing the piston 31 to be moved to open exhaust-ports 37 when a predetermined pressure has obtained in the brake-cylinder in service action, thereby preventing the admission thereto of any pressure greater than such predetermined amount. In emergency action the sudden admission of a high pressure to the brake-cylinder forces the piston 31 to a farther travel, bringing the larger part of the stem 36 over the ports 37, causing a slow initial reduction and a subsequent rapid reduction as the smaller diameter of the sleeve passes by such ports, this reduction being in proportion to the decrease in speed of the train. When the pressure has been reduced to the predetermined amount, the piston 31 seats its valve 32 and holds that pressure in the brake-cylinder until the brakes are released. Whether the brake is working as an ordinary automatic or high-speed brake, there is no danger either in service or emergency applications of the sliding of the wheels of the car here understood to be empty. At this time the parts of the automatic controller remain in normal position shown in Fig. 3, inasmuch as they become operative only after the operating-lever and valve are turned. When the car is loaded, the trainman in passing along the side of the car thrusts one of the rods 40 or 41 inward, with the result that the valve is partially rotated in an anticlockwise direction to the position shown in Fig. 4, whereupon the supplemental-reservoir port 9 is put into communication with valve-chamber 11, and consequently with the auxiliary reservoir, so that the braking may now be performed with the combined pressures of both said reservoirs and with increased power. At the same time the recess 22 of the disk valve is carried beyond the range of the blow-down port 25, thereby destroying the normal communication between the brake-cylinder and the blow-down device. At the same time also the valve-port 21 registers with controller-port 26, (see Figs. 4 and 10,) so that reservoir-pressure is admitted through port and passage 26, through cavity 52, port 53 into chamber 45^a behind or on the right of piston 45, Fig. 4, such piston having of course been drawn to seated position by the same movement which operated the disk valve. The air-pressure thus operating against the piston 45 now holds the rod

44, as well as the disk valve, in loaded-car position against the tension of spring 54 and after the trainman has withdrawn his hand from the bleed-rod which he had operated. Inasmuch as the piston seats on the left-hand end of the chamber 45^a the pressure so admitted thereto cannot leak off, and consequently the disk valve is automatically held in loaded-car position so long as the air-brake system of the car remains under pressure. When, however, the brake system of the car ceases to be under air-pressure from any cause, the chamber 45^a will also cease to contain air-pressure, and the spring 54 will thereupon restore the parts to normal or empty-car position, Fig. 3. The loaded-car position of the valve device is thus dependent upon the presence of air-pressure in the brake system of the car.

In case my automatic controller were dispensed with and provision made to hold the disk valve in any set position there is the danger that a careless trainman might omit to set the valve to empty-car position after the car had been unloaded, and so the braking of the empty car would be done with the increased volume of reservoir-pressure, with the result that the wheels would be skidded and injured. My automatic controller, however, is independent of the trainman in thus resetting itself and is dependent only upon the existence of air-pressure on the car. As is well known, the air-pressure on a detached car leaks off in a comparatively short time, lasting less than twenty-four hours, so that whenever a car supplied with my equipment is not in a live train, whether side-tracked for unloading or otherwise, the valve device will be restored to normal position, and in case the car remains loaded and is again put in a train the valve can be set to the loaded-car position again.

To bleed the auxiliary reservoir, the trainman pulls on either one of the bleed-rods in the usual manner, and thereby oscillates the disk valve in a clockwise direction to the position shown in Fig. 5, whereupon the valve-port 21 is brought into register with the release-port 27, and the reservoir is consequently "bled," as it is called in railroad parlance. At the same time the stem 44 is forced to the right, Fig. 5, and the follower-plate 55 also carried to the right, while the plate 56 is necessarily stationary, whereby the spring 54 becomes compressed. As soon as the operated bleed-rod is released the spring 54 restores all the working parts to normal position.

It is evident from the foregoing that my valve mechanism or device 6 provides means for producing a partial braking pressure for a car empty and a full braking pressure for a car loaded, and in its present and preferred form it also provides means for releasing or bleeding the auxiliary reservoir. When the automatic controller is employed, my valve mechanism is capable of being automatically held at loaded-car position so long as the air-brake system of the car remains charged with

air-pressure, and when such system ceases to be so charged such mechanism is capable of being automatically restored to empty-car position, which is the normal position. Cars 5 supplied with my equipment will therefore be braked in proportion to their empty or loaded weight and with the same reduction of train-pipe pressure.

I claim—

- 10 1. In combination with an air-brake system, an air - reservoir supplemental to the usual auxiliary reservoir, a brake-cylinder pressure-regulating device, a casing having a chamber provided with a valve-seat on whose 15 face terminate ports or connections respectively with the supplemental reservoir, brake-cylinder, the pressure-regulating device and the atmosphere, said chamber also having a communication with the auxiliary reservoir, 20 a rotary disk valve working on said seat and having means for controlling said various ports and connections, substantially as described, and means for operating the valve from the side of the car.
- 25 2. In combination with an air-brake system, an air - reservoir supplemental to the usual auxiliary reservoir, a brake-cylinder pressure-regulating device, a casing having a chamber provided with a valve-seat on whose 30 face terminate ports or connections respectively with the supplemental reservoir, brake-cylinder, the pressure-regulating device and the atmosphere, said chamber also having a communication with the auxiliary reservoir, 35 a rotary disk valve working on said seat and having the two ports 20 and 21 and recess 22 for controlling said ports and connections and having a valve-stem, an operating-lever secured to the stem, and operating-rods connected to the lever and extending to opposite sides of a car.
- 40 3. In combination with an air-brake system, an air - reservoir supplemental to the usual auxiliary reservoir, a brake-cylinder pressure-regulating device, a casing having a chamber provided with a valve-seat on whose 45 face terminate ports or connections respectively with the supplemental reservoir, brake-cylinder, the pressure-regulating device and the atmosphere, said chamber also having a communication with the auxiliary reservoir, 50 a rotary disk valve working on said seat and having the two ports 20 and 21 and recess 22 for controlling said valve-seat ports and connections, a valve - stem for operating said valve, a lever connected to said stem and having the opposite arms 38 and 39 and operating-rods connected to such lever-arms respectively and extending to opposite sides of a car.
- 55 60 4. In combination with an air-brake system, an air - reservoir supplemental to the usual auxiliary reservoir, a brake-cylinder pressure-regulating device, a casing having a chamber provided with a valve-seat on whose 65 face terminate ports or connections respectively with the supplemental reservoir, brake-cylinder, the pressure-regulating device and

the atmosphere, said chamber also having a communication with the auxiliary reservoir, a rotary disk valve working on said seat and 70 adapted to govern said ports and connections, a valve-stem detachably but operatively connected to such valve and extending through one side of the casing, operating devices secured to the valve-stem, a flange 15 on the 75 stem within the valve-chamber, and a gasket 16 on which such flange is seated.

5. In combination with an air-brake system, an air - reservoir supplemental to the usual auxiliary reservoir, a brake-cylinder 80 pressure-regulating device, a casing having a chamber provided with a valve-seat on whose face terminate ports or connections respectively with the supplemental reservoir, brake-cylinder, the pressure-regulating device and 85 the atmosphere, said chamber also having a communication with the auxiliary reservoir, a rotary valve 13 working on said seat to govern said ports and connections, valve-stem 14 for such valve, a cap 12 secured to the casing 90 and forming a wall of the valve-chamber, and provided with a central bore through which said stem passes, and means for operating the valve-stem and valve.

6. In combination with an air-brake sys- 95 tem, a supplemental air-reservoir, a brake-cylinder pressure-regulating device, a casing having a chamber provided with a valve-seat having terminating thereon a port 9 to the supplemental reservoir, a port 8 to the brake- 100 cylinder, a port 25 to the pressure-regulating device and a port 27 to the atmosphere, a disk valve having a recess 22 and two ports 20 and 21, the recess in normal position connecting ports 8 and 25, in loaded-car position, the ports 105 9 and 20 being in register to connect the two reservoirs and the recess no longer connecting ports 8 and 25 and in bleed position, the ports 21 and 27 being in register to release the auxiliary-reservoir pressure. 110

7. The combination with an air-brake system, a supplemental air-reservoir, a brake-cylinder pressure-regulating device, a casing having a valve-chamber provided with communication with the air-brake system, with 115 the supplemental reservoir and with the pressure-regulating device, the lower end or portion of the casing being formed as a screw-threaded extension by which the pressure-regulating device is received and a rotary 120 disk valve in said chamber to govern said communications.

8. In combination with an air-brake system, a supplemental air-reservoir, a brake-cylinder pressure-regulating device, a casing having a valve-chamber provided with communication with the air-brake system, with 125 the supplemental reservoir and with the pressure-regulating device, said casing having the auxiliary-reservoir connection 7, and a similar but normally closed connection 7^a, whereby the auxiliary-reservoir air may enter the chamber from either side, and a valve in said chamber to govern said communications. 130

9. In combination with an air-brake system, a supplemental air-reservoir, a brake-cylinder pressure-regulating device, a casing having a valve-chamber provided with communication with the air-brake system, with the supplemental reservoir and with the pressure-regulating device, said casing having the auxiliary-reservoir connection 7 and a similar but normally closed connection 7^a, both arranged above bottom of the chamber, whereby either connection may be used for the auxiliary-reservoir air and whereby also the one not used for this purpose may serve to permit introduction of a supply of oil in the chamber, and a valve in said chamber to govern said communications.
10. In combination with an air-brake system, a supplemental reservoir, a brake-cylinder pressure-regulating device, a casing having a valve-chamber provided with a vertical valve-seat on whose face terminate communications respectively with the supplemental reservoir, with the brake system and with the pressure-regulating device, a rotary disk valve working on said seat to govern said communications, said casing and chamber having the two auxiliary-reservoir connections 7 and 7^a either one of which may be used for the reservoir air and the other one of which is closed but adapted to act as an oiling-hole, said connections entering the chamber above the bottom whereby a supply of oil may be introduced so that the valve will work in oil.
- 35 11. In combination with an air-brake system and the usual bleed-rods thereof, a supplemental reservoir, a casing having a valve-chamber provided with communication respectively with the air-brake system, the supplemental reservoir and the atmosphere, a valve in said chamber to govern said communications, and an operative connection between the valve and bleed-rods whereby the usual pull on either rod bleeds or releases the auxiliary reservoir and an inward push on either rod operates the valve to connect the supplemental and auxiliary reservoirs for greater braking force for loaded cars.
12. In combination with an air-brake system and the usual bleed-rods thereof, a supplemental reservoir, a brake-cylinder pressure-regulating device, a casing having a valve-chamber provided with communication respectively with the brake system, supplemental reservoir, pressure-regulating device, and the atmosphere, a valve in said chamber to govern said communications and an operative connection between the valve and the bleed-rods whereby the usual pull on either rod bleeds or releases the auxiliary reservoir as heretofore while an inward push or thrust on either rod adjusts the valve to loaded-car position, the normal position of such valve and rods representing empty-car position.
- 65 13. In combination with an air-brake system comprising the train-pipe 1, triple valve 2, auxiliary reservoir 3, brake-cylinder 4, a supplemental reservoir 5, a pressure-regulating device, a valve device 6 having a chamber 11 in communication with the brake-cylinder through a port and passage 8, with the supplemental reservoir, through a port and passage 9, with the pressure-regulating device through a port and passage 25 and with the atmosphere through a port and passage 27, a disk valve 13 having the two transverse ports 20 and 21 and a recess 22, said chamber also having a port and passage 7 to the auxiliary reservoir, a valve stem 14 for the valve, an operating-lever connected to the stem and having the lever-arms 38 and 39 provided with lugs on their outer ends and the rods 40 and 41 connected respectively to said lugs of the lever-arms.
14. In combination with an air-brake system, means for producing a partial braking pressure for a car empty and full braking pressure for a car loaded, and mechanism governed by the pressure of the brake system for controlling said means and adapted to hold the same to loaded-car position, during the entire period of loaded-car braking.
15. In combination with an air-brake system, means normally adjusted to produce partial braking pressure for a car empty and adapted to be adjusted independently of the application of the brakes to produce full braking pressure for a car loaded, and mechanism dependent upon the pressure of the brake system for holding said means to loaded-car position and adapted to restore the same to normal or empty-car position.
16. In combination with an air-brake system, a device adapted to be adjusted for braking a car in proportion to its empty or loaded weight and means for automatically restoring such device to its empty position only when the air has substantially passed from the entire brake system.
17. In combination with an air-brake system, a device adapted to be adjusted independently of the application of the brakes for braking a car in proportion to its empty or its loaded weight, and means governed by the pressure of the brake system for restoring the device to normal position of light-weight braking.
18. In combination with an air-brake system, a device adapted to be adjusted for braking a car in proportion to its empty or loaded weight and normally maintained in empty-car position and mechanism governed by the pressure of the brake system to maintain said device in loaded-car position when so adjusted and so long as air-pressure remains in the brake system.
19. In combination with an air-brake system, a device for producing a partial braking pressure for a car empty and full braking pressure for a car loaded, a brake-cylinder pressure-regulator and mechanism actuated by the pressure of the brake system to maintain said device when adjusted for loaded-car braking.

20. In combination with an air-brake system, a device for producing a partial braking pressure for a car empty and full braking pressure for a car loaded, a brake-cylinder pressure-regulator, and fluid-pressure-actuated mechanism for maintaining said device when adjusted for loaded-car braking.
21. In combination with an air-brake system, a device adjustable for producing a partial braking pressure for a car empty and producing full braking pressure for a car loaded, a pressure-regulator for regulating the brake-cylinder pressure to a predetermined amount for said partial braking pressure, said regulator being cut out of service when full braking pressure is produced, and mechanism for holding said device when adjusted for full braking pressure so long as the brake system is charged with pressure.
22. In combination with an air-brake system, a device adjustable for producing a partial braking pressure for a car empty and producing full braking pressure for a car loaded, a pressure-regulator for regulating the brake-cylinder pressure to a predetermined amount for said partial braking pressure, said regulator being cut out of service when full braking pressure is produced, and mechanism for holding said device when adjusted for full braking pressure so long as the brake system is charged with pressure, and adapted to restore such mechanism to a normal position for partial braking pressure when the system ceases to be so charged.
23. In combination with an air-brake system, valve mechanism coöperating therewith and adapted when in one position to produce a predetermined or partial braking pressure in the brake-cylinder and in another position to produce a higher or full braking pressure therein, and in a third position to bleed the auxiliary reservoir of the brake system, and mechanism for restoring such valve mechanism to a normal position of partial braking pressure after adjustment to either of the other two positions.
24. In combination with an air-brake system, valve mechanism coöperating therewith and adapted when in one position to produce a predetermined or partial braking pressure in the brake-cylinder and in another position, to produce a higher or full braking pressure therein, and in a third position to bleed the auxiliary reservoir of the brake system, and mechanism actuated by the pressure of the brake system for restoring such valve mechanism to a normal position of partial braking pressure after adjustment to either of the other two positions.
25. In combination with an air-brake system, valve mechanism for producing a partial braking pressure for a car empty and a full pressure for a car loaded, and a fluid-pressure-actuated controller operated by pressure admitted by the valve mechanism when adjusted for full-pressure braking and having operating connection with the valve mechanism to

70 maintain it in such adjusted position so long as the brake system remains charged with pressure.

26. In combination with an air-brake system, valve mechanism for producing a partial braking pressure for a car empty and a full pressure for a car loaded, means for operating such valve mechanism and thereby adjusting it for an empty or a loaded car, a fluid-pressure-actuated controller and a connection between the controller and said operating means, said valve mechanism being arranged to admit the fluid-pressure of the brake system to the controller when the former is adjusted to loaded-car position, and to thereby maintain it in such position.

27. In combination with an air-brake system, valve mechanism for producing a partial braking pressure for a car empty and a full pressure for a car loaded, a valve-stem for said valve mechanism, an operating-lever on said stem, and a fluid-pressure-actuated controller connected to said lever, said valve mechanism being arranged to admit pressure from the brake system to the controller when the valve mechanism is adjusted to loaded-car position whereby such adjustment is maintained so long as the brake system is charged.

28. In combination with an air-brake system, valve mechanism for producing a partial braking pressure for a car empty and a full pressure for a car loaded, operating connections for the valve mechanism, a fluid-pressure-actuated controller connected to said connections and having means for maintaining a position of normal for itself and consequently such connections, said valve mechanism being arranged to admit pressure from the brake system to the controller when the valve mechanism is operated to loaded-car position to thereby maintain the valve mechanism in said latter position.

29. In combination with an air-brake system, valve mechanism for producing a partial braking pressure for a car empty and a full pressure for a car loaded, operating connections for the valve mechanism, a fluid-pressure-actuated controller connected to said connections, and a spring for holding said controller and connections in a normal position for partial braking pressure for an empty car, said valve mechanism being adapted when adjusted to loaded-car position against the tension of the controller-spring to admit pressure to the controller to overcome the spring-pressure and maintain the valve mechanism in said adjusted position.

30. In combination with an air-brake system, an air-reservoir supplemental to the usual auxiliary reservoir, a fluid-pressure-actuated controller, a valve device having communication respectively with the supplemental reservoir, auxiliary reservoir and the controller and adapted to govern such communications, operating devices connected to such valve device and to the controller whereby when the valve device is adjusted to connect

the two reservoirs, air-pressure is admitted to operate the controller through whose connection with the valve device the latter is maintained in such adjusted position so long as

5 the brake system is charged with pressure.

31. In combination with an air-brake system, an air-reservoir supplemental to the usual auxiliary reservoir, a fluid-pressure-actuated controller, a valve device having communication respectively with the supplemental reservoir, auxiliary reservoir and the controller and adapted to govern such communications, a valve-stem for such valve device, an operating-lever having operating devices 15 running to the sides of the car, and a connection between the controller and the lever.

32. In combination with an air-brake system, an air-reservoir supplemental to the usual auxiliary reservoir, a fluid-pressure-actuated controller, a valve device having communication respectively with the supplemental reservoir, auxiliary reservoir and the controller and adapted to govern such communications, a valve-stem for such valve device, 25 an operating-lever having operating devices running to the sides of the car and a connection between the controller and the lever, said controller comprising a piston working in a chamber and having a stem connected to said 30 connection.

33. In combination with an air-brake system, an air-reservoir supplemental to the usual auxiliary reservoir, a fluid-pressure-actuated controller, a valve device having communication respectively with the supplemental reservoir, auxiliary reservoir and the controller and adapted to govern such communications, a valve-stem for such valve device, an operating-lever having operating devices 35 running to the sides of the car, and a connection between the controller and the lever, said controller comprising a piston working in a chamber and having a stem connected to said connection and a spring against whose tension the piston moves.

34. In combination with an air-brake system, valve mechanism for producing a partial braking pressure for a car empty and a full pressure for a car loaded, a fluid-pressure-actuated controller operated by pressure 40 from the valve mechanism when adjusted to loaded-car position and comprising a casing having a chamber, a piston therein having a projecting stem, a spring against whose tension the piston moves, operating devices for the valve mechanism and a connection between such stem and the said devices.

35. In combination with an air-brake system, valve mechanism for producing a partial braking pressure for a car empty and a full pressure for a car loaded, a fluid-pressure-actuated controller operated by pressure 45 from the valve mechanism when adjusted to loaded-car position and comprising a casing having a chamber, a piston therein having a projecting stem, such chamber having a port through which the pressure is admitted be-

hind the piston, a spring against whose tension the piston moves, an operating-lever for the valve mechanism, and a pivotal connection between the piston-stem and lever. 70

36. In combination with an air-brake system, valve mechanism for producing a partial braking pressure for a car empty and a full pressure for a car loaded, a fluid-pressure-actuated controller operated by pressure 75 from the valve mechanism when adjusted to loaded-car position, and comprising a casing having a chamber, a piston therein having a stem projecting through the chamber and when moved to loaded-car position adapted to seat at one end of the chamber to prevent leakage around the stem, and a connection between the stem and valve mechanism.

37. In combination with an air-brake system, valve mechanism co-operating therewith and adapted when in one position to produce a predetermined or partial braking pressure in the brake-cylinder and in another position to produce a higher or full braking pressure 90 therein, and in a third position to bleed the auxiliary reservoir of the brake system, a controller actuated by pressure from the valve mechanism when adjusted to full braking pressure 95 and comprising a casing having a chamber, a piston therein having a stem operatively connected to the valve mechanism, a double-acting spring holding the piston in normal position against movement in either direction. 100

38. In combination with an air-brake system, valve mechanism co-operating therewith and adapted when in one position to produce a predetermined or partial braking pressure in the brake-cylinder, and in another position 105 to produce a higher or full braking pressure therein and in a third position to bleed the auxiliary reservoir of the brake system, a controller actuated by pressure from the valve mechanism when adjusted to full braking pressure 110 and comprising a casing having a chamber, a piston therein having a stem operatively connected to the valve mechanism, follower-plates on the stem, a double-acting spring between said plates and abutments within the 115 chamber for limiting the movements of the plates.

39. In combination with an air-brake system, valve mechanism for producing a partial braking pressure for a car empty and a full 120 pressure for a car loaded, an operating-lever connected to the valve mechanism and having arms 38 and 39, operating-rods 40 and 41 connected to said arms, a branch 50 on the arm 38 having bearing-lugs 49, a controller actuated by pressure from the valve mechanism 125 when adjusted for full braking pressure and having a movable stem 44 and a link connection 48 between the stem and said bearing-lugs. 130

40. In combination with an air-brake system, an air-reservoir supplemental to the usual auxiliary reservoir, a valve-casing having a chamber in communication with the supple-

mental reservoir, auxiliary reservoir, and with a controller, and also having an extension forming a controller-chamber, a valve in said valve-chamber for governing said communications, an operating-lever for said valve, a piston arranged in said controller-chamber and having a stem operatively connected to said lever and a spring against whose tension the piston as well as the valve is moved.

10. 41. In combination with an air-brake system, a supplemental reservoir, a valve device adapted, when adjusted to loaded-car position to connect said reservoir with the usual auxiliary reservoir of the air-brake system, and 15 means for holding the valve device in such adjusted position so long as the brake system of the car is under air-pressure.

42. In combination with an air-brake system, a reservoir supplemental to the usual 20 auxiliary reservoir of the brake system, a valve device adapted, when adjusted to loaded-car position, to connect the two reservoirs whereby the pressures of both are made available to obtain increased braking force and 25 means governed by the pressure of the brake system and coöperating with the valve device to maintain it in such adjusted position during all loaded-car brakings.

43. In combination with an air-brake system, a reservoir supplemental to the usual 30 auxiliary reservoir of the brake system, a valve device adapted, when adjusted to loaded-car position, to connect the two reservoirs and a fluid-pressure-actuated device coöperating with said valve device to maintain it in such adjusted position during all loaded-car brakings.

44. In combination with an air-brake system, a reservoir supplemental to the usual 40 auxiliary reservoir of the brake system, a valve device adapted, when adjusted to loaded-car position, to connect the two reservoirs to obtain increased braking force, and a controller coöperating with the valve device to 45 maintain it in such adjusted position, said valve device itself initially governing said controller.

45. In combination with an air-brake system, a reservoir supplemental to the usual 50 auxiliary reservoir of the brake system, a valve adapted, when adjusted to loaded-car position to connect the two reservoirs and a fluid-pressure-actuated controller coöperating with said valve device to maintain it in 55 such adjusted position, said valve device governing the admission of fluid-pressure to said controller.

46. In an air-brake system, the usual auxiliary reservoir for producing a partial or 60 empty car braking pressure, in combination with a supplemental reservoir for producing a full or loaded car braking pressure, a device adapted to be adjusted to connect said reservoirs and also to bleed the auxiliary reservoir and controlling mechanism for maintaining said device, after adjustment, at a position to connect said reservoirs, said device

itself governing the operation of said mechanism.

47. In combination with an air-brake system, a reservoir supplemental to the usual auxiliary reservoir of the brake system, a valve device adapted when adjusted to loaded-car position to connect the two reservoirs and also adapted in another adjusted position 75 to bleed the auxiliary reservoir, and a controller coöperating with the valve device to maintain it in its loaded-car position, said valve device itself initially governing said controller. 80

48. In an air-brake system for producing light and heavy braking, the combination of a casing having a chamber communicating with the auxiliary reservoir and filled with the air thereof and also having an opening to 85 atmosphere, a supplemental reservoir also communicating with said chamber, and adapted to control said opening to bleed the auxiliary reservoir and also adapted to govern communication between said reservoirs, a spring 90 holding the valve to its seat and maintaining the supplemental-reservoir pressure after the auxiliary-reservoir pressure has been vented from said chamber, and a fluid-pressure controller operatively connected to said valve to 95 hold it in a position for establishing communication between said reservoirs and having a port or passage communicating with said chamber and governed by the said valve.

49. In an air-brake system, an auxiliary reservoir for light braking, a supplemental reservoir adapted to be combined, as to its pressure, with such auxiliary reservoir to produce heavy braking, in combination with a rotary disk valve provided with an operating-stem 105 and adapted to connect or disconnect the two reservoirs, and a spring coiled around the valve-stem and arranged to hold the valve to its seat to thereby maintain the supplemental-reservoir pressure regardless of any decrease 110 in the auxiliary-reservoir pressure.

50. In combination with an air-brake system, means for obtaining in the brake-cylinder a certain braking pressure when a car is empty and capable of adjustment for obtaining in the brake-cylinder a greater or increased braking pressure when the car is loaded, and mechanism governed by the pressure of the brake system for controlling said means and adapted to hold the same to loaded-car position. 115 120

51. In combination with an air-brake system, means adapted to produce partial braking pressure for a car empty and manually adjustable for producing a full and increased 125 braking pressure for a car loaded, and mechanism governed by the pressure of the brake system for controlling said means and adapted to hold the same to its adjusted position of loaded-car braking so long as the brake system of the car is under pressure.

52. In combination with the usual air-brake system having a single brake-cylinder, means for producing in said cylinder a partial brak-

ing pressure for a car empty and a full or increased braking pressure in said cylinder for a car loaded, and mechanism governed by the pressure of the brake system for controlling said means and adapted to hold the same to loaded-car position.

53. In combination with the usual car-brake system having a single brake-cylinder, means for producing a light braking force for a car empty and a heavy braking force for a car loaded, and mechanism manually adjustable for said heavy braking and controlling said means, said mechanism being arranged to automatically return to light braking position

15 when the air-pressure passes from the brake system.

54. In combination with an air-brake system, means for producing a partial braking pressure for a car empty and full braking

pressure for a car loaded and adapted to be 20 adjusted, independently of the pressure of the brake system, to a position for loaded-car braking, and mechanism governed by the pressure of the brake system for controlling said means and adapted to hold the same to 25 loaded-car position.

55. In combination with an air-brake system including the auxiliary reservoir, means for producing a partial braking pressure for a car empty and full braking pressure for 30 a car loaded and mechanism governed by the auxiliary-reservoir pressure for controlling said means.
